W. L. HANCOCK

COTTON HULLER BREAKER BAR

Filed Feb. 24, 1925

UNITED STATES PATENT OFFICE.

WILLIAM L. HANCOCK, OF DALLAS, TEXAS, ASSIGNOR TO THE MURRAY COMPANY, OF DALLAS TEXAS, A CORPORATION OF TEXAS.

COTTON-HULLER BREAKER BAR.

Application filed February 24, 1925. Serial No. 11,094.

To all whom it may concern:

Be it known that I, WILLIAM L. HANCOCK, a citizen of the United States, residing at Dallas, in the county of Dallas and State 5 of Texas, have invented certain new and useful Improvements in Cotton-Huller Breaker Bars, of which the following is a specification.

My invention is an improved breaker bar 10 for a cotton hulling and cleaning machine and is more particularly an improvement upon the breaker bar shown and described in my Letters Patent of the United States, No. 1,526,144, dated February 10, 1925.

15 In the drawings:

Figure 1 is an end elevation of a part of a hulling and cleaning machine such as is shown in Figure 1 of my Patent No. 1,526,144, showing my improvements and 20 their relation to the old parts, the inner parts being in dotted lines;

Figure 2 is a front view of my improved breaker bar, on a larger scale, looking in the direction of the double arrow, Figure 1;

25 Figure 3 is a view of an end of the breaker bar of Figure 2, in plan, both ends being identical in construction;

Figure 4 is a section on line 4—4 of Figure 2; and

30 Figure 5 is a detail of a tooth.

The cotton is fed to the huller cleaner through chute 8 and reaches the feed rolls 9, turning as indicated by the arrows, by which it is fed in a somewhat compressed 35 bat to the breaker roll 10 rapidly turning in the direction indicated by the arrow, the teeth 10^a of the roll 10 strike the bat hammer like blows, breaking the bolls, without grinding them. All this is shown and 40 described in my Patent No. 1,526,144, and is repeated here to make clear the relations of the novel parts to be described. I have marked the parts of the old machine hereinabove mentioned in accordance with their 45 indicating numbers in Patent No. 1,526,144.

To one side and in front of the breaker roll 10 is set a cooperating shaft 111 supported in bearings 112, in the frame 113 of the machine. This shaft 111 carries at 50 either end brackets 114, secured to the shaft by set screws 115 or otherwise, and carrying seats 116 on its depending ends for a transverse angle plate 117 which is fast upon the seats of the two end brackets and 55 connects the depending ends of the brackets.

Between the hubs of the brackets 114 and filling the space I mount upon the shaft 111 a multiplicity of teeth, 118, the hubs 118^a of which are free to turn upon the shaft. Rearwardly extending from each hub 60 118^a is a tail-piece 118^b projecting across the upper edge of the cross member 117. At the free end of each tail-piece 118^b is attached a tension spring 119 the lower end of which is attached to the lower part of 65 the cross-member 117 (see Figure 4). It is obvious, of course, that in place of the tension spring a spring of another form or type might be employed or the weight of the tail-piece might be relied on to normally hold the tooth in position. These 70 are obvious equivalents.

At one end of shaft 111 is secured by set screws or the like the hub 120^a of a lever 120 (see Figures 1 and 2) the hub serving 75 also as a collar to restrain longitudinal movement of the shaft 111, in cooperation with collar 111^a at the other end of the shaft. This lever 120 is connected by a link member 121 with a position securing device 80 122, preferably a toothed sector and latch as shown in Figure 1. It will now be obvious that the shaft 111 with its brackets 114 and cross member 117 may be swung and secured in a desired position and in 85 this way the teeth 118 may be set forward or back toward the roll 10 and across the path of the material, the teeth 118 passing in their advanced position, between the rows of teeth 10^a, on the roll 10. Beneath the 90 teeth 118, across the machine, is set a comb with upstanding teeth 18, the teeth 18 being opposite the rows of the teeth 10^a on the roll 10 and between the teeth 118. When the teeth 118 are retracted by turning the 95 shaft 111 they are received in the spaces between the teeth 18 and a continuous surface is then presented upon that side of the cotton passage.

It will now be clear that the teeth 118 may be adjusted, advanced or retracted, by turning the shaft 111 and locking it in position by means of the latch and toothed-sector mechanism, 122. Also that in case any hard material, such as for example, a stone, 100 passes the feed rolls 9, and is carried down upon the teeth 118, only the tooth or teeth directly in its path will be affected and that this tooth or teeth can yield downward under the impact against the force of a spring 105 110

119 and as soon as the stone or other object has passed, the tooth affected will return to its adjusted position, the shaft 111 and the other teeth upon it, being unaffected 5 and continuing to perform their designed function without interruption.

I claim:

1. In a boll-breaker and cotton cleaner, a chute; a boll breaker roller beneath the 10 chute; a shaft in front and to one side of the roller; brackets fast at either end of the shaft; a cross-member connecting the brackets; teeth loosely mounted upon the shaft with capacity to turn thereon, the 15 rear end of the teeth normally resting upon the cross-member.

2. In a boll-breaker and cotton cleaner, a chute; a boll breaker roller beneath the chute; a shaft to one side and in front of the roller; brackets fast at either end of the 20 shaft; a cross-member connecting the brackets; teeth loosely mounted upon the shaft with capacity to turn thereon the rear end of the teeth extending over the cross-member; means to keep each tooth normally 25 pressed against the cross-member with liberty to turn away from it; means to turn the shaft and teeth and secure them in a designed position.

Signed at Dallas, Texas, this 16th day 30 of February, 1925.

WILLIAM L. HANCOCK.
